PNEUMATIC ACTION OF MECHANICAL PLAYERS FOR MUSICAL INSTRUMENTS

Filed Jan. 4, 1922

UNITED STATES PATENT OFFICE.

HENRY THOMSON, OF WAVERLEY, NEAR SYDNEY, NEW SOUTH WALES, AUSTRALIA.

PNEUMATIC ACTION OF MECHANICAL PLAYERS FOR MUSICAL INSTRUMENTS.

Application filed January 4, 1922. Serial No. 526,894.

To all whom it may concern:

Be it known that I, HENRY THOMSON, a subject of the King of Great Britain, residing at "Echo," 33 Evans Street, Waverley, 5 near Sydney, in the State of New South Wales, Commonwealth of Australia, have invented new and useful Improvements in Pneumatic Actions of Mechanical Players for Musical Instruments, of which the following is a specification.

This invention relates to improvements in pneumatic actions of mechanical players for pianofortes and other musical instruments, and in particular to a new and improved 15 construction of valve casing and valve integers, and arrangement of the same relatively to the vacuum chest and an operating pneumatic, whereby functional and constructional advantages in player actions, 20 now unobtainable with existing constructions, will be had.

It is an object of the invention to provide a simple and compact valve structure characterized by having air-tight seats for 25 the valve-head, and constructed in such manner that the distance between said seats in each of the series of actions is identical.

A further object of the invention is to provide a valve structure wherein the top plate (now detachably fitted above the valve-head) is integral with the valve casing, and wherein the requirement of having a cap detachably fitted with screws or like fastenings beneath the valve diaphragm is 35 dispensed with.

A still further object of the invention is to provide a compact valve structure having a valve-head chamber and a diaphragm chamber integrally formed with the valve casing and means whereby the former is in direct communication with the operating pneumatic through the top plate thereof, and the latter is in direct communication with the vacuum chest. By these means I 40 dispense with conduits or passages hitherto proposed, and eliminate friction and cushioning of air in said conduits, whereby the functional advantage of better repetitive work and lighter pedalling action is obtained in a specially simple and positive manner.

With these and other objects in view the invention consists of the features of con-

struction, combination and arrangement hereinafter fully described, reference being had to the accompanying drawings, wherein:

Figure 1 is a view in side elevation illustrating the valve casing constructed integrally with the top plate of an operating pneumatic, and rigidly secured to the vacuum chest.

Figure 2 is a vertical section of the upper portion of Figure 1.

Figure 3 is a sectional plan on line 1—1 of Figure 1.

Figure 4 is a view in vertical section illustrating the means of direct communication between the diaphragm chamber and the vacuum chest.

Figure 5 is a plan of the valve-casing and integral top plate of the pneumatic.

Figure 6 is an underside plan of Figure 5 illustrating the port providing direct communication of the valve-head chamber with the pneumatic, through the top plate of the latter.

Figure 7 is a front elevation of the valve casing, and illustrates the positions of the tracker tube conduit, and a rigid disc of the diaphragm integer of the valve.

Figure 8 is a rear elevation of the valve casing, and illustrates the outlet port from the diaphragm chamber.

Figure 9 is a side elevation of the valve casing, and illustrates the rigid disc of the diaphragm with attached tracker tube conduit.

Figure 10 illustrates the construction of the rigid diaphragm disc.

Figure 11 is a vertical section illustrating a modification in the construction of the valve casing.

In these views 11 designates the casing of a vacuum chest 12 adapted for fixture with in the pianoforte casing in approved manner and location. 13 indicates the operating pneumatic and 14 the top plate thereof.

Each of the series of pneumatics is preferably of that construction having two parallel floating plates 15 and 16 and a flexible envelope 17, said floating plates being adapted to be drawn towards the stationary plate upon the collapse of the pneumatic following exhaust of air therefrom.

These pneumatics are preferably ar-

ranged in a single longitudinal row, as is described in the specification of co-pending application for Letters Patent Serial Number 424,811 filed 18th November, 1920.

5 The construction and the arrangement of the operating pneumatics do not form any part of the present invention, and it will be understood that the improved valve structure may be employed with pneumatics 10 of other type than that illustrated, such as pneumatics of conventional character having a stationary top plate and a lower plate hingedly connected thereto at one end.

15 Constructed integrally with the pneumatic top plate 14 by metal die-casting operations is a valve casing 18 having a bracket 19 to facilitate its attachment to the vacuum chest casing by means of a fastening screw 20, and a vertical partitioning wall 21

20 providing a valve-head chamber 22 and a diaphragm chamber 23 disposed on opposite sides of said wall, wherein is formed a central inter-communicating port 24.

25 The valve-head chamber has a port 25 in its outer wall for the intermittent admission of atmospheric air as hereinafter explained, and on its underside it has a port 26 formed through said top plate 14 in order to be in direct communication with the interior of the collapsible pneumatic 13, thereby obviating the necessity of providing a special conduit or passage for the purpose. Small holes are provided in the opposite walls of the chamber 22 to receive a pin or 30 dowel 27 to retain the valve-head 28 in constant operative position within its chamber. The inner faces of the walls of the chamber 22 surrounding the ports 24 and 25 form alternative seatings for said valve-head, and 35 as the valve casing is produced by die-casting operations, the distance between these seatings is identical throughout the series of actions, thereby ensuring uniformity of valve action.

40 45 The diaphragm chamber 23 consists of a circular recess having a locating shoulder 29 for a flexible diaphragm 30 of leather or like flexible material, and constructed with a groove 31 to take over the tubular nipple 32 for connection to a tracker tube 33.

50 Formed in the rear wall of the diaphragm chamber is an elongated slot 34 enlarged at 35 and functioning as a port arranged for direct communication between said chamber and the vacuum chest 12. This construction dispenses with the hitherto proposed inclined passage connected at one end to the valve casing and at its other end to the vacuum chest, and eliminates friction 55 and cushioning of air such as would be prejudicial to rapid repetition work and tending to relatively heavy pedal action.

60 65 The ports 25 and 26 of the valve-head chamber, the port 24 in the partitioning wall 21, and the elongated slot 34 in the

70 wall of the diaphragm chamber are all produced in the operation of die-casting the valve casing 18. Consequently economy of manufacture and accuracy of production are obtained.

75 The valve-head 28 consists of a plurality of thin leather discs affixed together by rubber solution or other adhesive, and its travel is limited by the distance apart of the seatings in its chamber 22.

80 I provide a diaphragm supporting disc 36 which is of a diameter to having a driving fit with the chamber 23. This disc is preferably constructed of ebony, but it may be made of wood, suitable composite material or as a metal stamping, and it has a concave inner face forming an air space 37 behind the diaphragm 30.

85 Said disc 36 is formed with a port 39 leading into the air space 37 from the tracker tube connecting nipple 32, and it has a bleed hole 40 which registers with the enlarged portion 35 of the slot 34 when the valve integers are assembled.

90 Consequently said bleed hole communicates directly with the vacuum chest, and it enables the tracker tube 33 to be pneumatically exhausted. A slight suction is thus produced in the tracker tube sufficient to exhaust the air therefrom when a duct 95 in the tracker bar is covered by the music sheet and prevent the operation of the valve, but insufficient to exhaust it when said duct is open. This suction retains the music sheet in close contact with the tracker bar 100 in the operation of the player mechanism, as will be readily understood.

105 A disc 41 of fabric gauze is provided at the rear of the diaphragm 30 for the purpose of filtering the air admitted to said air space 37 through the tracker tube. This filter disc and the flexible diaphragm are affixed in position to the supporting disc 36 by adhesive applied to their edges.

110 The valve stem 42 is affixed at one end to the inner face of the valve-head 28, and at its opposite end to a disc 43 of stout paper fastened to the diaphragm 30. The valve-stem may, however, be formed integrally with the disc 43 which latter may be formed of papier-mâché or other suitable material having the properties of lightness and durability.

115 120 In assembling the integers of the improved valve structure, the valve-head 28 is inserted in the chamber 22 when the retaining dowel 27 is driven into the holes provided therefor in the valve casing. Adhesive for the outer end of the valve-stem 42 is placed centrally on the inner side of said valve-head. The rigid disc 36 fitted with the tubular nipple 32, filtering screen 41, flexible diaphragm 30, and valve-stem 42 is then placed into the circular recess forming the diaphragm chamber 23, the groove 125 130

31 receiving said nipple and thereby functioning as a guide for correct location.

The disc 36 is then driven inwardly until the edge of the diaphragm 30 abuts against 5 the locating shoulder 29. A coating of shellac is then applied around said diaphragm supporting disc, thereby ensuring that a perfectly air-tight joint is effected between the same and the diaphragm chamber 10 23 of the valve casing, and dispensing with the requirement of providing a cap or cover element with ordinary attachment screws or the like.

According to the modification illustrated 15 in Figure 11, the port 26 leading directly from the valve-head chamber 22 to the operating pneumatic 13 through its top plate 14 is made slightly less in length than the diameter of the valve-head 28. Formed in 20 the end wall of said chamber 22 is a slot 43 of such length and width as will permit the valve-head being readily inserted into its chamber for assembly of the valve integers, when an air-tight cover 44 of leather 25 or other suitable material is firmly secured over said slot as by the use of an adhesive. The provision of this slot 43 allows inspection or removal and replacement of the valve-head to be effected merely by removing 30 the cover 44, thereby avoiding the necessity of removing the fabric 17 of the pneumatic 13 for such purpose.

When the musical instrument is not in use, the valve-head 28 is seated against the 35 partitioning wall 21 closing communication between the valve-head chamber 22 and the vacuum chest 12. Atmospheric air passes into said chamber 22, thence directly to the pneumatic 13 permitting the latter to be 40 maintained inflated.

In action and when the perforated sheet, travelling across the tracker-bar closes a duct in the latter, a vacuum is formed in the space 37 behind the flexible diaphragm 30 45 permitting it to rest in a neutral or inoperative position which condition is aided by the exhaust of air through the bleed hole 40. The valve-head 28 then rests upon its inner seat in the partitioning wall 21.

50 When the tracker-bar duct is opened by a perforation in the travelling music sheet coinciding therewith, atmospheric air is admitted to the space 37 behind the diaphragm 30 in greater quantity than can be exhausted 55 through the small bleed hole 40. The diaphragm 30 is of larger area than the valve-head 28, as is illustrated, and advantage is thereby taken of the larger area of diaphragm material which is exposed to vacuum, and notwithstanding the weakening caused by the exhaust through the bleed hole 40, a force is exerted on said diaphragm 30 overbalancing the atmospheric pressure exerted on the valve-head 28, causing the latter to be thrown rapidly across from its

inner seat against the wall 21 to its outer seat around the port 25, thereby closing communication between the atmosphere and the pneumatic 13. The pneumatic is then directly connected to the vacuum chest 12 by 70 way of port 26 in the top plate 14, the port 24 in the partitioning wall 21 and the elongated slot 34 in the wall of the diaphragm chamber 23, causing the exhaust of the pneumatic and by its collapsing action the actuation of the pianoforte action to strike a note.

When the duct in the tracker-bar is subsequently closed by the travelling music sheet, the valve-head 28, having a constant 80 tendency to be seated against the partitioning wall 21 by atmospheric pressure, acts through the valve-stem 42 on the ballooned diaphragm 30, similarly as if impelled by a weak spring, thereby forcing the entrapped air in the space 37 outwardly through the bleed hole 40 into the vacuum chest 12 until the valve-head is permitted to resume its inner seat, opening the port 25 to atmosphere when the diaphragm 30 is 90 brought to its neutral or inoperative position.

Although the valve casing in its preferred embodiment is constructed by metal die-casting operations, it will be understood 95 that a valve structure according to my invention and within the scope of the appended claims can be made of wood or other approved material and produced by any means found suitable in manufacturing 100 operations.

What I do claim is:—

1. In pneumatic actions of players for musical instruments, an operating pneumatic having a plate constituting a fixed 105 wall thereof arranged with an integral laterally extending casing arranged with a valve chamber therein in communication with the pneumatic through an opening in the plate, a diaphragm chamber arranged 110 in said casing, aligned openings in opposite walls of the casing one of said openings communicating with the diaphragm and valve chambers of the casing and the other in open communication with the valve chamber and atmosphere, and a valve in the valve chamber connected with the diaphragm through the opening connecting the diaphragm and valve chambers to control said openings and operative to connect 115 the pneumatic with the diaphragm chamber and to shut the pneumatic off from the atmosphere or to connect the pneumatic with the atmosphere and shut it off from the diaphragm chamber for the purpose specified.

2. Operating pneumatics for pneumatic players for musical instruments as claimed in claim 1 in which the casing having the diaphragm and valve chambers is arranged 130

- with a slot in the lateral wall of the casing for insertion and removal of the valve, and a removable air tight closure for said slot.
3. In pneumatic actions of mechanical players for musical instruments, a vacuum chamber, an operating pneumatic including a plate with a casing constructed integral therewith having a partition to arrange said casing with a valve chamber and a diaphragm carrying chamber at opposite sides of said partition, said partition having a port to connect said chambers, a port in the wall of the valve chamber in opposed relation to the port in the partition opening to the atmosphere, a port in the plate in communication with the valve chamber and pneumatic, a valve in the valve chamber connected to the diaphragm through the port connecting said chambers operative from the diaphragm to control the opening and closing of the ports in the partition and the port opening to the atmosphere, and a port in the wall of the diaphragm chamber in communication with the vacuum chamber.
4. In pneumatic actions of mechanical players for musical instruments, a vacuum chest, an operating pneumatic including a rigid plate having a casing integral therewith and arranged as a bracket to mount the pneumatic upon the vacuum chest, said casing having a partition to arrange the same with a valve carrying chamber and a diaphragm chamber and having a port therein to connect said chambers, a port in the wall of the valve chamber in opposed relation to the port in the partition opening to the atmosphere, a port in the plate to connect the valve chamber and pneumatic, a port in the wall of the diaphragm chamber at one side of the diaphragm and communicating with a port in the vacuum chest, a port in the wall of the diaphragm chamber at the opposite side of the diaphragm arranged for connection to a tracker tube, and a valve in the valve chamber connected to the diaphragm through the port connecting said chambers and operative from the diaphragm to control the opening and closing of the port in the casing partition and the port in the valve chamber opening to the atmosphere.
5. In pneumatic actions for mechanical players of musical instruments, a valve casting constructed with a recess forming a diaphragm chamber, a rigid disc, a flexible diaphragm secured to said disc and an air space between said disc and said diaphragm, said disc tightly fitting said recess to form a closure to said diaphragm chamber.
6. In pneumatic actions for mechanical players of musical instruments, a valve casting constructed with a recess forming a diaphragm chamber, a rigid disc concaved on its inner side, a flexible diaphragm secured to said disc, an air space at the rear of said diaphragm, a bleed hole in said disc, and a tracker tube, tubular connection fitted to said disc and communicating with said air space, said disc being adapted to form a closure to said diaphragm chamber.
7. In pneumatic actions for mechanical players of musical instruments, a valve casting constructed with a chamber accommodating a valve-head and with a diaphragm chamber, an inter-communicating port between said chambers, a slot in a wall of said diaphragm chamber, a rigid disc having a concave inner face and tightly fitting said diaphragm chamber, a diaphragm secured to said disc and having an air space at its rear, a tubular nipple for connection to a tracker tube fitted to said disc and communicating with said air space, a bleed hole in said disc registering with said slot, a valve-stem affixed at one end to said diaphragm and at its opposite end to said valve-head.
8. In pneumatic actions for players for musical instruments, a pneumatic including a plate having an integral casing with a partition separating the casing into a valve chamber and a recess at the opposite side of said partition, a closure for the recess carrying a diaphragm at the inner side with a space between the closure and diaphragm, a port in said partition to connect the valve chamber and recess at one side of the diaphragm, a port in the wall of the valve casting in opposed relation to the partition port opening to the atmosphere, a port in the plate to connect the pneumatic and valve chamber, a port in the wall of the recess at one side of the diaphragm for connection to vacuum creating means, a bleeder opening in the closure in communication with the recess port and with the space between the diaphragm and recess closure, a second port in the recess closure in communication with the space between the closure and diaphragm arranged for connection of a tracker tube, a valve in the valve chamber to control the opening and closing of the opposed ports in the wall of the valve chamber and partition, and a stem to operatively connect the valve with the diaphragm through the port of the partition.

In testimony whereof I affix my signature.

HENRY THOMSON.
